UNITED STATES PATENT OFFICE.

MYERS A. GARRETT, OF CHICAGO, ILLINOIS, ASSIGNOR TO CARLTON M. GARRETT, OF CHICAGO, ILLINOIS.

AIR MOISTENER AND DUST ARRESTER.

1,426,286.

Specification of Letters Patent. Patented Aug. 15, 1922.

Application filed April 4, 1921. Serial No. 458,363.

To all whom it may concern:

Be it known that I, MYERS A. GARRETT, a citizen of the United States, residing at Chicago, in the county of Cook and State of Illinois, have invented certain new and useful Improvements in Air Moisteners and Dust Arresters; and I do hereby declare the following to be a full, clear, and exact description of the invention, such as will enable others skilled in the art to which it appertains, to make and use same.

The object of my invention is twofold, to wit: the provision of an effective air moistener or humidifier for the air of rooms heated by steam or hot water through the medium of radiators, and also in connection therewith the provision of means for removing dust and other particles of matter from the air in which they are suspended, both said means functioning simultaneously.

The desirability of humidifying the heated air in a room and removing impurities carried thereby in suspension, in the interests of health and cleanliness, are well known and need not be specified.

The invention consists in certain novelties of construction and in the combination of parts as herein set forth and claimed.

The accompanying drawing illustrates an example of the embodiment of the invention, the parts being constructed and combined according to one of the best methods of procedure I have so far devised for the purpose.

Figure 1 is an end view in elevation, showing a radiator with the improved air moistener and dust arrester supported thereupon.

Figure 2 is a front view in elevation of Figure 1, the right hand portion of the moistener being broken away to show the construction.

Figure 3 is an enlarged sectional view in elevation of the upper part of Figure 1.

Figure 4 is a top plan view of part of Figure 1 and on the same scale as Figure 3.

Figure 5 is a top plan view of the perforated, removable cover, the right hand end being broken away to show the location of the frame and its covering.

Referring to the figures of the drawing, the numeral 1 designates a steam or hot water radiator of any type; 2, a water tank or reservoir preferably made of sheet metal, rectangular in cross section, closed at the bot-

tom and open at the top; 3, 3, metallic hooks or curved metallic bars secured at their rear ends to the vertical wall of the tank by rivets or otherwise, their front ends being extended over and resting upon the connections which unite the sections of the radiator; and 4 is a metallic frame for supporting the removable cover carrying an air moistener and dust arrester proper.

The frame 4 comprises an angle iron 5 having its vertical flange extended about and riveted to the open end of the water tank on three sides thereof, and the opposite free ends 6 of said angle iron are of sufficient length to extend over the top of the radiator; an angle iron 7 having its horizontal flange secured to the horizontal flange of the angle iron 5 and extended entirely around the top of the radiator, the same being rectangular in shape; and an ornamental apron 8 secured at its top edge to the vertical flange of the angle iron 7 and its lower edge extending downwardly over the top of the radiator so as to conceal the top parts thereof at the ends and front; otherwise stated, the ornamental apron laps over the top, front and ends of the radiator.

The projecting ends of the angle iron 5 may rest upon the sections of the radiator, and, being securely riveted to the top edge 85 of the tank on three sides thereof, may aid in supporting the tank and holding it in proper position; in fact, if the frame 4 be strong enough, it may support the water tank and the apron hold it in place. 90

A sheet metal cover 9 rectangular in plan and perforated as shown has its longitudinal edges turned to form recesses 10, 10, the cover, when in position, resting upon the horizontal flange of the angle iron 7, as 95 shown by Figure 3.

A rectangular skeleton frame 11 over which is slipped a baffle cloth 12 of bag shape provides two parallel layers of cloth spaced apart for absorbing the watery vapor evaporated from the tank and for arresting the dust in the air when the latter passes through the cloth. The frame 11 is supported at its edges in the recesses 10, 10 of the cover and it can be inserted and withdrawn endwise relative to the cover when one end of the cover is raised. 100

Figure 1 shows the radiator spaced a slight distance from a partition 13 and baseboard 14 with the tank located between 110

and extending downwardly near the floor, thus affording capacity for a relatively large quantity of water. 55 eterious effects, and is also a source of annoyance when deposited upon the walls and furnishings of a room.

When the parts are constructed as described and the appliance placed upon a radiator as shown, the operation is as follows: The water becoming heated passes in the form of vapor upwardly to the baffle cloth which becomes moistened as it retains 10 some of the vapor. The remainder of the vapor mingled with the hot air arising around the radiator and beneath the apron passes through the holes in the cover to the atmosphere of the room which is moistened 15 thereby.

It is well known that the air in a room heated with steam or hot water through the medium of a radiator when it comes in contact with the hot radiator ascends or 20 rises, inasmuch as heated air is lighter than cold air, and then becomes diffused throughout the air of the room, a constant circulation or movement of the air thus being maintained. As is well known, air in a room 25 carries dust which is evidenced by its deposition upon the walls and furnishings of the room.

A radiator provided with my appliance obviously will remove the greater part of 30 the dust and light particles of matter held in suspension by the air in a room. The heated air ascending through the open spaces between the radiator sections and beneath the apron can escape only by passing 35 through the moistened baffle cloth and out through the openings in the cover, and the greater part of the dust carried thereby will be caught and retained by the moist baffle cloth.

40 As the dust laden air repeatedly becomes heated and passes through the baffle cloth nearly all the dust is finally removed therefrom, leaving none to settle on the walls and furnishings, consequently the task of 45 dusting is thereby obviated.

From the foregoing description taken in connection with the drawing it is clear that I have provided a means for not only moistening the air in a room to the desired degree of humidity necessary to health, but have also provided in connection therewith 50 means for the effective removal of dust and foreign matter from the air which, when present, is drawn into the lungs with del-

What I claim is:

1. The combination in a device of the character described for radiators, of a tank 60 for water having an open top; a housing including an angle iron 7 extending entirely around the housing, and an apron, said housing being secured to the top of the tank so as to project at right angles from 65 one side of the body of the tank far enough to cover the top of a radiator; a removable cover with a perforated top supported upon one flange of the said angle iron and held in position by the other flange of the angle 70 iron; and a dust arrester located at the under surface of the cover, said arrester being supported by the cover and bodily removable therefrom.

2. The combination in a device of the 75 character described for radiators, of a tank for holding water having an open top, a frame secured to the tank at the top thereof and extending substantially at right angles to the tank so the frame will engage the 80 top of a radiator and support the tank, a removable cover with openings carried by the frame, and a dust arresting means carried by and removable with the cover.

3. The subject-matter of claim 2 with the 85 addition of an apron in connection with the frame which apron when the device is in use extends over the top of a radiator and confines and deflects the ascending air through the dust arresting means. 90

4. The combination in a device of the character described for radiators, of a tank for holding water having an open top; a frame secured to the tank at the top thereof and extending substantially at right angles 95 to the body of the tank so the frame will overlap the top of the radiator when in position; a removable cover with openings carried by the frame; a dust arresting means below and carried by and removable with 100 the cover; and bars secured to one side of the body of the tank and projecting therefrom substantially parallel with the frame for supporting the tank at one side of and upon a radiator. 105

In testimony whereof I affix my signature.

MYERS A. GARRETT.
